UNITED STATES PATENT OFFICE.

JOHN J. CRANDALL, OF PHILADELPHIA, PENNSYLVANIA, ASSIGNOR TO
JACOBS W. SCHUCKERS, OF NEW YORK, N. Y.

IMPROVEMENT IN REVOLVING BOOK-CASES.

Specification forming part of Letters Patent No. 177,993, dated May 30, 1876; application filed
January 11, 1876.

To all whom it may concern:

Be it known that I, JOHN J. CRANDALL, of the city and county of Philadelphia, in the State of Pennsylvania, have invented certain new and useful Improvements in Revolving Book-Cases, of which the following is a specification:

The object of my invention is to provide a revolving book-case which shall be light, simple, and inexpensive in its construction, and capable of easy rotation without liability to derangement of its parts; to which ends my improvements consist in the combination of a vertical central standard, having a step or center at its top, a metallic frame or spider secured to the top of the case, and resting upon the bearing of the central standard, and a bottom plate (in one or more sections) connected with the upper spider by bolts passing through intermediate hollow posts, and which is provided with a central opening, through which the vertical standard passes, and which acts as a guide to the case, to prevent vibration in its rotation around the standard, all as hereinafter more fully set forth.

In the accompanying drawings, Figure 1 is a view, in elevation, of a revolving book-case embodying my improvements; Fig. 2, a vertical central section of the same; Fig. 3, a horizontal section, showing the bottom plate in view; and Fig. 4, a top view with the cover removed.

To carry out the object of my invention I provide a vertical standard or column, A¹, mounted in the center of a metallic frame or disk, A, supported on suitable feet a. The lower end of the standard is slightly conical, and is fitted in a corresponding socket in the frame A. A metallic step or center bearing, A², is secured upon the top of the standard A¹. The case is composed of a top plate, B, bottom plate B', (each in one or more pieces,) inner casing E, sides D, and shelves G, the

whole united by vertical bolts F. The sides may be three or more in number, six being shown in this instance; and in order to make the spaces for the reception of the books as nearly parallel upon their sides as practicable, the sides D are made in the form of hollow posts or casings, preferably triangular in section. The bolts F pass through the hollow posts, and are secured to the bottom plate B by nuts and washers. The upper ends of the bolts pass through a corresponding number of arms, c, on a metallic plate or spider C, which rests on the top plate B, and is provided at its center with a projection, which fits into a central opening of the top plate B, and has a bearing, c', for the step or center A². Additional clamps c² secure the arms of the spider C to the top plate B of the case, and to the top plate of the inner casing E. The bottom plate B' is provided with a central opening, b, which encircles the standard A¹, for the purpose of guiding the case in its rotation about the standard, and of preventing vibration of the case when rotated. The vertical spaces or divisions formed between the hollow posts D may be divided horizontally by any desired number of shelves G to receive the books.

The frame A may be constructed with three or more sockets, into which the legs a are fitted and secured.

I claim as my invention and desire to secure by Letters Patent—

The combination, in a revolving book-case, of a top plate, a bottom plate, a series of intermediate hollow posts or casings, a frame or spider secured to the top plate, and a series of vertical tie-bolts, substantially as set forth.

JOHN J. CRANDALL.
